UNITED STATES PATENT OFFICE

JØRGEN SEIDELIN LOTTRUP, OF COPENHAGEN, DENMARK

APPARATUS FOR ACCOMMODATING OBJECTS TO BE DELIVERED OR HANDED OUT

Application filed September 8, 1930, Serial No. 480,534, and in Denmark September 9, 1929.

This invention relates to an apparatus, the purpose of which is to receive objects especially small objects such as tickets, coins and similar things, which are to be handed out or delivered.

Apparatus of this kind are known as so called coin trays, such trays consisting of a substantially horizontal receiving plate or tray, which is brought into a sloping position at the time of delivery, so that the coins by gravity slide down the same.

The objects of the invention is to provide an apparatus of the kind in question, which takes up a limited space only, that the apparatus can be operated by one hand only, that it can be made double acting, so that it can be operated from both sides, and furthermore it should be easy to handle and absolutely safe and reliable in operation.

The apparatus indicated by the present invention is distinguished by the fact, that a flap is hinged to the receiving plate, directly or indirectly at each end or one end, which flap serves to act upon the receiving plate in order to bring the same into a sloping position, and at the same time forms a sliding plane for the objects to be delivered.

The drawing represents schematically various embodiments of the invention.

Figure 1 shows an apparatus according to the invention in normal position,

Figure 2 the same in position for delivery,

Figure 3 another embodiment,

Figure 4 is a third embodiment in normal position,

Figure 5 the same in one of the positions of delivery,

Figure 6 a front view of one of the flaps of the apparatus and

Figure 7 the same seen from below in Figure 6.

In the embodiments shown the apparatus consists of a receiving plate *a*, to which, at opposite ends and at a distance from the edges, are hinged flaps *b* shaped as two armed

levers movable on fixed pivots *c*. In the embodiments shown in Figures 1 to 3 the flaps are hinged directly to the plate by means of pivots *d*.

The normal position of the receiving plate *a* is the horizontal position. In this position the plate is held by springs not shown in the drawing. These springs also serve to return the plate to normal position. The normal position may be secured by stops. 50

In the embodiment shown the receiving plate *a* is supported solely by the flaps *b*. The plate *a* is brought from the normal horizontal position to the sloping position of delivery by an outwardly directed pull acting upon the lower end of one of the flaps *b*. 55

When the apparatus shown in Figure 1 is acted upon as indicated by an arrow the moving system consisting of the plate *a* and the flaps *b* is brought to the position shown in Figure 2. The plate *a* is thereby brought into a so sloping position that coins etc. placed on the plate gravity slide down the plate and further over the left hand flap *b*, now lying in continuation of the plate *a*. 60 70 The sliding coins are caught by the hand operating the apparatus. The best method of use is by means of the fingers to act upon the back of the lower part of the flap which for this purpose may be furnished with a downwardly inclined flange *k*. When loosening hold of the apparatus the moving system is returned to normal position by the previously mentioned springs. 75

In the apparatus shown in Figures 1 and 2 a fixed frame *e* is shown, which does not move together with the receiving plate *a*. In normal position the frame *e* forms an upright flange along the edges of the plate *a* thus preventing the coins from sliding out over the edge when carelessly thrown on the plate. As shown in Figure 2 the frame *e* does not impair with the movement of the receiving plate *a*. 80 85

In Figure 3 the frame *e* is firmly connected 90

to the receiving plate *a* and so shaped that the coin can slide over the frame at opposite sides. To prevent a free fall of the coins the flaps *b* are bent in this case, so that the coins having passed the inclined flange of the frame, slide over on the flap. In Figure 3 one of the positions of delivery is shown in dotted lines.

In the embodiment of the invention shown in Figures 4 and 5 the flaps *b* are not hinged directly to the receiving plate *a*, but the connection is established by links *f*, formed by plates arranged beneath the plate *a* substantially parallel to the same and in such a manner that they from normal position can be swung in one direction only. Similarly, the flaps *b* are swingable in one direction only from the normal position of Figure 4, movement in the opposite direction being prevented by fixed stops *g*. Furthermore these stops serve to fix the plate *a* in normal position, as the plate cannot be brought out of horizontal position by a pressure at its upper side.

By acting upon the left hand flap *b* in the direction indicated by the arrow in Figure 4 the apparatus is brought into the position of delivery, Figure 5. During the movement to this position the left hand link *f* remains abutting against the lower side of the plate *a*. The right hand flap *b* does not swing as in the previously shown embodiments in the clockwise direction but remains stationary in its position resting against the corresponding stop *g*. On the other hand the right hand link *f* swings in the clockwise direction relatively to the corresponding flap, so that the right hand end of the plate *a* is raised to a greater extent than in the embodiment shown in Figures 1 and 2.

As shown in Figures 6 and 7 the flaps *b* can be provided with upstanding flanges *h*, converging downwards, so that the coins are carried together while moving downwards. It may be preferred to give this flange *h* such a shape, as shown in Figure 7, that they at the top join the flap *b* at a sharp angle, while at the lower end the joint is rounded. This rounding *j* can then decrease upwards.

The invention is not restricted to the embodiments shown in the drawing but these embodiments can be altered in various ways without departing from the spirit of the invention.

Having thus fully described my invention I claim as new and desire to secure by Letters Patent:

1. An apparatus for accommodating objects to be delivered comprising a normally horizontal receiving plate and at least one flap positively connected to one end of the said plate, said flap serving for acting upon the said plate to bring the same into a sloping position and forming a sliding plane for the objects to be delivered.

2. An apparatus for accommodating objects to be delivered comprising a normally horizontal receiving plate and two flaps positively connected to the said plate at opposite ends thereof, said flaps serving for acting upon the said plate to bring the same into a sloping position, so that it forms a sliding plane for the said objects, and at the same time supporting the said plate. 70

3. An apparatus for accommodating objects to be delivered comprising a normally horizontal receiving plate and at least one two armed lever, one arm of this lever being positively and movably connected to the said plate and the other arm being adapted to be 80 acted upon by hand in order to bring the said plate into a sloping position.

4. An apparatus according to claim 3 in which the said lever is positively connected to the adjacent end of the receiving plate at 85 a distance from its edge.

5. An apparatus for accommodating objects to be delivered comprising a normally horizontal receiving plate, two flaps positively connected to the ends of the said plate 90 and forming together the sole support for the same, and a frame surrounding the horizontal receiving plate, each of said flaps serving for acting upon the said plate to bring the same into a sloping position and forming a sliding plane for the objects to be delivered. 95

6. An apparatus according to claim 5 in which the said frame is stationary.

7. An apparatus for accommodating objects to be delivered comprising a normally horizontal receiving plate and two flaps connected to the said plate at opposite ends thereof at a distance from the edge by means of links, said links being normally substantially parallel to the said plate, from which position they can be swung in one direction only, said flaps acting as levers and serving, through the links, to affect the receiving plate to bring the same into a sloping position and also for supporting the receiving plate in all positions thereof. 110

8. An apparatus according to claim 7 in which each of the said flaps rests against a stop in order to secure the said plate in its normal position. 115

9. An apparatus according to claim 7 in which each flap is provided with upstanding downwards converging flanges.

10. An apparatus according to claim 7 in which each flap is provided with upstanding flanges joining the flap at a sharp angle at the top while at the lower end the joint is rounded, the said rounding decreasing gradually upwards. 120

11. An apparatus according to claim 7 in which each flap is provided with a projection at its back face and at its lower end, said projection being adapted to be acted upon by the fingers and to create a free fall 125

of the objects to be delivered from the flap to the hand.

12. An apparatus for accommodating objects to be delivered comprising a support, a normal horizontal receiving plate, and two flaps swingable in relation to the said support and connected to the said plate at opposite ends thereof, said flaps forming together the sole support for the receiving plate.

10 In testimony whereof I have affixed my signature in presence of two witnesses.
